(57) **CLAIM**

We claim the ornamental design for an informational display assembly for a gaming table as shown and described.

DESCRIPTION

FIG. 1 is a reduced top perspective view of an informational display assembly for a gaming table, showing our new design, installed within a gaming table;

FIG. 2 is a top perspective view thereof, showing a display screen in one position;

FIG. 3 is a top perspective view thereof, showing a display screen in another position;

FIG. 4 is a top plan view of the perspective view of FIG. 2;

FIG. 5 is a top plan view of the perspective view of FIG. 3;

FIG. 6 is a bottom plan view thereof;

FIG. 7 is a front elevation view thereof;

FIG. 8 is a rear elevation view thereof;

FIG. 9 is a right side elevation view thereof; and,

FIG. 10 is a left side elevation view thereof.

The phantom line showings throughout the views are for illustrative purposes only and form no part of the claimed design.
